AUTOMATIC WEATHER STRIP AND
SILENCER

James K. Robinson, Tampa, Fla.

Application January 15, 1935, Serial No. 1,948

2 Claims. (Cl. 20--68)

The device forming the subject matter of this application is used for stopping a draft of air beneath a door. The device comprises a wind check. The invention aims to improve the construction of the wind check, to provide novel means for guiding the wind check in its movements, and to provide novel means for actuating the wind check.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, 20 may be made within the scope of what is claimed, without departing from the spirit of the invention.

In the drawings:

Fig. 1 shows in elevation, a door and its mountings, parts of the door being broken away to disclose the working mechanism, and parts being shown in section;

Fig. 2 is a section on the line 2--2 of Fig. 1;

Fig. 3 is a section on the line 3--3 of Fig. 1;

Fig. 4 is a section taken on the line 4--4 of Fig. 1;

Fig. 5 is a sectional view on the line 5--5 of Fig. 1;

Fig. 6 is a vertical section on the line 6--6 of Fig. 1;

Fig. 7 is a fragmental horizontal section showing one of the fillers.

The numerals 1 and 2 designate door posts. A closure, such as a door 3, is hinged at 4 to the door post 1, to swing horizontally. There is a rebate 5 in the door post 1. The door post 2 has a rebate 6. The door post 2 has a slanting surface 7 leading to the rebate 6. The door 3 fits in the rebates 5 and 6, when the door is closed, as shown in Fig. 3.

The door 3 has a recess 8 in its lower edge. The recess 8 extends from the inner edge of the door to the outer edge thereof. A carrier plate 9 is let into the inner edge of the door 3 and closes one end of the recess 8. The carrier plate 9 is held in place by securing elements 10. The carrier plate 9 has a lower guide 11, in the form of a rib, extending into the recess 8 of the door 3. The carrier plate 9 is supplied, above the guide rib 11, with an upper tubular guide 12,

disposed horizontally and extended into the recess 8 of the door 3. A similar carrier plate 14 is secured at 15 to the outer edge of the door 3 and closes the corresponding end of the recess 8. The carrier plate 14 has a vertical guide rib 16, corresponding to the guide rib 11 of the plate 9. The carrier plate 14 has a tubular guide 17, corresponding to the guide 12 of the plate 9. The bore of the guide 12 is circular, however, whereas the bore of the guide 17 is rectangular in cross section. Figure 1 shows that the guide 12 is spaced a little below the lower edge of the recess 8, whereas the guide 17 abuts against the door 3 at the upper edge of the recess 8. An opening or notch 19 is formed through the guide 17 and the plate 14 from side to side. Angular fillers 18 (Fig. 7) are secured in the rebates 5 and 6 of the door posts 1 and 2 respectively. The fillers comprise parts which extend across the door posts 1 and 2, under the plates 9 and 14, when the door is closed as shown in Fig. 1.

An anchor plate 20 is let into the door post 2, within the rebate 6. The anchor plate 20 is secured to the door post 2. The anchor plate 20 carries a transverse arm 21, resting against the beveled surface 7 of the door post 2. The arm 21 is of such width that it can pass through a notch 19 in the parts 17 and 14, when the door 3 is closed, as in Fig. 1. The arm 21 has an inclined surface 22.

The numeral 23 designates a vertically movable wind check located in the recess 8 of the door 3. The wind check 23 is a composite structure. It includes a bar or body 24. The body 24 is provided at its ends with heads 25, slidably mounted on the guide 11 of the plate 9 and on the guide rib 16 of the plate 14. The construction is such that the part 24 can move vertically, but not endwise. An inverted trough-shaped base piece 26 is secured to the lower edge of the body 24. A weather strip 27, made of felt or any other suitable material is secured in the base piece 26. The base piece 26 is provided intermediate its ends with upstanding flanges 28. Shafts 29 are mounted in the flanges 28. Rollers 30 are journaled on the shafts 29 and are disposed between the flanges 28.

The numeral 31 designates, generally, an operating member mounted for right line movement. The operating member 31 includes an intermediate section or rod-like body 32. The rod 32 is supplied at one end with a ball 33 slidably received in the guide 12 of the plate 9. On its opposite end, the rod 32 has a ball 34 received in a seat 35 formed in the end of a slide 36. The slide 36

36 is mounted to reciprocate in the guide 17 of the plate 14. A roller 37 is journaled on the outer end of the slide 36. The roller 37 is horizontally disposed. The slide 36 corresponds in cross section to the guide 17, the slide cannot turn on its axis, and, consequently, the roller 37 keeps the horizontal position shown in Fig. 3. The roller 37 is adapted to ride along the inclined surface 22 of the arm 21 on the anchor plate 20, when the door 3 is closed. The slide 37 is provided with a shoulder 38 which, cooperating with the inner end of the guide 17, limits the movement of the operating member 31 to the right in Fig. 1.

15 Abutments 39, 40 and 41 are secured at 42 to the intermediate section 32 of the operating member 31. The abutment 40 is an intermediate abutment. The abutment 39 is disposed between the abutment 40 and the slide 36. The abutment 20 41 is located between the abutment 40 and the tubular guide 12.

Raising and lowering members 43 are mounted movably on the rod 32, but keep a fixed position thereon. One of the raising and lowering members 43 engages the abutment 41, under the action of a compression spring 45 surrounding the rod 32 and interposed between the abutment 40 and the raising and lowering member under consideration. The other raising and lowering member 43 engages the abutment 39, under the action of a compression spring 46 engaged between the said abutment and a washer 47, the washer 47 abutting against the inner end of the slide 36. A washer 48 is mounted on the rod 32 and engages the inner end of the guide 12. A compression spring 49 is mounted on the rod 32 and engages the abutment 41 and the washer 48. The raising and lowering members 43 extend downwardly between the upstanding flanges 28 of the body 24 of the wind check 23 and have inclined slots 44 wherein the rollers 30 on the body 24 of the wind check 23 operate.

When the door 3 is open, the spring 49 moves the operating member to the right and causes the roller 37 to outstand beyond the plate 14. As the operating member 31 is carried to the right, the slots 44 in the members 43, cooperating with the rollers 30 on the wind check, to raise the wind check. When the door 3 is closed, the roller 37 on the operating member 31 rides along the inclined surface 22 of the fixed ramp 21, the operating member 31 is carried to the left, and the slots 44 in the parts 43, cooperating with the rollers 30, carry down the wind check 23 and cause the weather strip 27 to close the space beneath the door 3. When the door 3 is closed, and when the operating member 31 moves to the left, the rod 32 can slide a little in the parts 43, the springs 45 and 46 being compressed, this construction avoids shocks, the springs acting as cushioning springs.

Although the member 23 has been called a wind check, it will of course serve to stop water, insects and sound from entering beneath the door 3. The part 23 is automatic, self-adjusting and flexible in operation and will serve as an adequate closure for the space between the floor and the lower edge of the door. It adapts itself to structural irregularities in the door or in the floor, and is easily installed.

Having thus described the invention, what is claimed is:

1. In a device of the class described, first and second carriers, means for mounting the carriers on opposite edges of a closure, a check, means for mounting the check for vertical movement; an operating member comprising a body, and a slide mounted for straight line movement on the first carrier and movable outwardly beyond the first carrier for engagement with a closure frame; means for mounting the body for longitudinal sliding movement on the second carrier and for pivotal movement thereon, a pivotal connection between the body and the slide of the operating member, said pivotal connection and the pivotal mounting of the body on the second carrier avoiding a flexing of the operating member when the closure warps, interengaging parts on the check and on the body of the operating member, cooperating to lower the check when the operating member is moved inwardly, and spring means for moving the operating member outwardly, when the closure is opened, thereby to raise the check.

2. In a device of the class described, first and second carriers, means for mounting the carriers on opposite edges of a closure, a check, means for mounting the check for vertical movement; an operating member comprising a body, and a slide mounted for straight line movement on the first carrier and movable outwardly beyond the first carrier for engagement with a closure frame; means for mounting the body for longitudinal sliding movement on the second carrier and for pivotal movement thereon, a pivotal connection between the body and the slide of the operating member, said pivotal connection comprising ball and socket elements, an abutment on the body of the operating member, a raising and lowering member slidable on the body of the operating member, interengaging elements on the check and on the raising and lowering member, cooperating to lower the check when the operating member is moved inwardly, spring means for moving the operating member outwardly, when the closure is opened, thereby to raise the check, and a compression spring interposed between the raising and lowering member and the slide, the last-specified spring acting as a cushion and as a means for holding the raising and lowering member yieldably engaged with the abutment.

JAMES K. ROBINSON.
